WHEEL

George M. Bellairs, Webb City, Mo., assignor to Grand
Foundries, Inc., Springfield, Mo., a corporation of
Missouri

Filed Mar. 15, 1963, Ser. No. 73,980

Term of patent 14 years

(Cl. D14—30)

FIGURE 1 is a front elevation view of a wheel embodying my new design;

FIGURE 2 is a side plan view of the wheel of FIGURE 1;

FIGURE 3 is a rear elevation view of the wheel of FIGURE 1;

FIGURE 4 is a sectional view taken along line 4-4 of FIGURE 3.

The characteristic features of my design reside in the arrangement and configuration of the spokes relative to the main body of the wheel as shown.

I claim:

The ornamental design for a wheel, substantially as shown and described.
